3 SHEETS—SHEET 3.

UNITED STATES PATENT OFFICE.

CLARENCE H. CALDWELL, OF OAK PARK, ILLINOIS.

TYPEWRITER ATTACHMENT.

1,424,985.

Specification of Letters Patent.

Patented Aug. 8, 1922.

Application filed June 1, 1920. Serial No. 385,475.

To all whom it may concern:

Be it known that I, CLARENCE H. CALDWELL, a citizen of the United States, and a resident of the village of Oak Park, in the 5 county of Cook and State of Illinois, have invented certain new and useful Improvements in a Typewriter Attachment; and I do hereby declare that the following is a full, clear, and exact description of the same, 10 reference being had to the accompanying drawings and to the numerals of reference marked thereon, which form a part of this specification.

This invention relates to an improved attachment for typewriters adapted to support sheets of copy in position directly over the platen or roller of the machine and at a convenient angle.

A further object of the invention is to 20 provide an improved copy holding attachment for typewriters which may be folded to inoperative position and take up a minimum of space so that the typewriter can be covered or disposed within a desk without 25 the necessity of removing the attachment.

Another object of this invention is to provide a copy holder which will be as close to the platen of a typewriter as is possible without interfering with the movement of 30 the paper or the carriage.

A still further object of the invention is to provide an attachment for typewriters which is adapted to allow the copy to be shifted upwardly a line at a time thus obviating the 35 possibility of skipping lines and allowing the operator to more easily find the particular words being copied.

Other and further important objects of this invention will be apparent from the disclosures in the specification and drawings.

The invention (in a preferred form) is illustrated in the drawings and hereinafter more fully described.

On the drawings:

Figure 1 is a side elevation of the improved typewriter attachment as applied to a conventional type of machine.

Figure 2 is a front view of same.

Figure 3 is a section taken on the line 3—3 50 of Figure 1, looking in the direction indicated by the arrows.

Figure 4 is a rear view of the attachment.

Figure 5 is a section taken on the line 5—5 of Figure 4.

Figure 6 is a section taken on the line 6—6 55 of Figure 4.

Figure 7 is a side view of one of the supporting arms.

Figure 8 is a section taken on the line 8—8 60 of Figure 2, looking in the direction indicated by the arrows.

As shown on the drawings:

The reference numeral 10 indicates a typewriter of conventional make, having my improved attachment applied thereto. Clamps 65 12 are provided with set screws 14 mounted therein, said clamps 12 being adapted to engage convenient portions of the frame of the machine 10, and to be firmly held in place by the set screws 14. The clamps 12 have bifurcated extensions 16 in which are pivotally mounted the semi-circular supporting arms 18. The pivot pins upon which the arms 18 are mounted are fixed to the arms to move therewith and each pin is provided with an 70 integral bevel gear 20 on its lower end. These bevel gears 20 mesh with corresponding gears 22, one fixed to each end of a transversely extending rod 24, said rod being journaled in downwardly extending ears 26 75 80 fixed to or integral with the clamps 12.

At their upper ends the semi-circular arms 18 are provided with flat bearing seats 28 having pins 30 extending upwardly from the centers thereof. These pins 30 have their longitudinal axes in the same vertical line as the axes of the pivot pins upon which the gears 20 are mounted. Supported by the bearing seats 28 and held in revoluble position by the pins 30 are the supporting arms 85 32 (Figs. 1, 4 and 7). These arms 32 are provided with cylindrical lugs 34 at their free ends, each of said lugs being provided with a longitudinally extending opening coaxial with a corresponding opening in the other lug. A shaft 36 passes through and is preferably fixed in the two lugs 34, which are provided with extensions 38 as shown in Figures 4 and 6.

Pivoted on the shaft 36 and adjacent the 100 lugs 34 are the arms 40, which normally extend downwardly to support the copy holder in position. At their lower ends, the arms 40 are pivoted at 42 to a transversely extend-

ing rod 44 supported in brackets 46 struck from and integral with the back plate 48 of the copy-holder. This plate 48 is preferably made from aluminum or any other light but strong metal and has made integral therewith four ears 50, two on each side edge thereof and bent upwardly therefrom at right angles thereto. These ears 50 are for the purpose of supporting the bearing shafts 52 and 54, having sprocket wheels 56 fixed thereon at each end. A chain 58 passes over each pair of sprocket wheels and a knurled knob 60 is fixed to the left hand end of the lower shaft 54 for normal operation of same. 10

Situated between the sprocket chains 58 and lying wholly in the same plane therewith, both in front and rear, is the support 62 composed of some light flexible material such as celluloid or the like attached to end plates 64, best shown in Figure 1. The two end plates are held together by transverse bolts 66 and are provided with bearing holes to accommodate the shafts 52 and 54. Overlying the support 62 and slideable thereon is the transverse rod 68 fixed at each end thereof to the sprocket chain 58. Slideable on the rod 68 are the clips 70 having downwardly and inwardly extending lugs 72 (Fig. 8) adapted to hold the clips 70 in slidable relation to the rod 68. The clips are provided with a thumb operated lever 74 which is held in normal paper engaging position by a spring 76 coiled around the pivot pin 78.

The lower shaft 54 is held in position by means of a spring pressed latch 80, and a line marker 82 pivoted in the ears 50 at 84 and 86 is provided, which also holds the paper in position and is maintained in normal position by a spring 88. The plate 48 is extended in the form of a semi-circular guard 90.

The operation is as follows:

The clamps 12 having the brackets 18 pivotally attached thereto, together with the shaft 24 and the gears 20 and 22, are first attached to the typewriter 10 and securely fixed in place by means of the set screws 14. Obviously the clamps 12 and the shaft 24 may be changed to conform to any type of machine. These parts are all made of iron, steel or some like material and the purpose of the gears is to facilitate the simultaneous turning of the arms 18 about the pivots 16 and 30 whenever it is desired to fold the attachment into a more compact form to allow of its being covered or disposed within a desk. Normally the brackets 18 are extended at approximately a 45° angle to permit of the free movement of the paper in the carriage of the machine.

The brackets 32, connected by the rod 36 and supporting the remainder of the device, are next put into position on the pins 30. 65 This leaves the copy holder in position as

shown in the full lines of Figure 1 ready to be used and the paper to be copied is laid upon the support or casing 62 and held in position by the clips 70, which are slideable on the rod 68 in order to be adjustable for any width and thickness of paper. The lines to be copied are brought around to the line marker 82 by turning the knob 60. In the case of very lengthy paper, as the copying progresses, the paper is simply allowed to pass over the top and around the celluloid casing 62, or, by bringing the clips down and refastening the paper, it will pass over and in back of the holder. The lugs 38 operate to keep the rods 40 from dropping into a vertical position, and thereby the copy holder is maintained at the proper angle. The movement of the paper is produced by turning the knob 60, which in turn acts on the sprockets 56 and chains 58, thereby giving motion to the cross strip 68 on which the paper is attached by means of the clips 70.

It will be noted that the holder swings up to a stationary position in back and over the top of the typewriter. This movement is performed by lifting on the support 62, causing the links 40 to swing about the rod 36 as a pivot until these links are stopped by contact with the other faces of the extensions 38. This brings the links to a definite stop in the nearly vertical position illustrated in dotted lines in Figure 1. If desired the support 62 may be left in the upper position illustrated in dotted lines and the friction will be sufficient to hold it in that position. It may however, if desired, be pushed to the rear until stopped by contact of plate 48 and links 40. This extreme rearward position is not illustrated. The position shown in dotted lines affords sufficient room for the insertion of paper into the typewriter or for viewing the typed matter. In this way paper can be inserted in the typewriter without interference. This also allows erasures to be made as well as making it possible to see the matter previously written.

In order to allow the typewriter with its attachment to be closed in a cabinet desk or to be covered, as the case may be, the holder may be swung down into the position shown in dotted lines in Figure 1, the rods 40 going upwardly as shown and the bracket arms 18 can be simultaneously turned inwardly on their respective pivots, the gears acting also to maintain the top and bottom pivots in axial alignment. The shafts 52 and 54, together with the sprockets and chains and the casing 62, can be readily removed for purposes of cleaning and repairs by merely displacing the latches 80, whereupon the shafts can be lifted out of their respective journals.

It will be seen that herein is provided a

copy holding attachment for typewriters which can be readily attached and easily removed, which can be shifted into three positions with a minimum of effort, a paper inserting position, an operative position and a folded inoperative position, and which can be easily taken apart for purposes of cleaning, and is of neat appearance, light and compact.

10 I am aware that numerous details of construction may be varied through a wide range without departing from the principles of this invention, and I therefore do not purpose limiting the patent granted 15 otherwise than necessitated by the prior art.

I claim as my invention:

1. A rod, a support for said rod, two links mounted to swing about said rod, stops mounted on said rod to limit the swing of 20 said links, a second rod connecting the free ends of said links, and a copy holder pivotally mounted on said second rod.

2. An attachment for typewriters comprising two brackets adapted to be fixed to 25 the machine, a supporting arm pivoted to each bracket on pins, a gear on the ends of each pin, said gears being so connected as to operate simultaneously, and a copy supporting stand positioned on the brackets.

30 3. A device of the character described comprising a pair of pivoted brackets, arms mounted thereon and a copy holding carriage pivotally mounted on the arms, said carriage being provided with means for shifting the copy one line at a time.

40 4. A device of the character described comprising a pair of pivoted brackets, arms pivotally mounted thereon, a plate pivotally mounted on the arms, said plate being provided with two pairs of upstanding lugs, a shaft revolvably supported by each pair of lugs, and a movable copy holder supported by said shafts.

45 5. A device of the character described comprising a pair of pivoted brackets, arms pivotally mounted thereon, a plate pivotally mounted on the arms, said plate being provided with two pairs of upstanding lugs, a shaft revolvably supported by each pair of lugs, a sprocket on the end of each shaft, chains around each pair of end sprockets, a support mounted on the shafts and between

the chains, and adjustable clips supported by said chains in movable relation to the support.

55

6. A device of the kind described comprising two adjustable clamps, a semi-circular bracket mounted in each clamp on a pivot pin, a gear on the end of each pivot pin, lugs depending from the clamps, a single revolvable shaft mounted in the lugs, and gears on the ends of the shaft adapted to coact with the gears on the pivot pins.

7. A device of the kind described comprising two adjustable clamps, a semi-circular bracket mounted in each clamp on a pivot pin, a gear on the end of each pivot pin, lugs depending from the clamps, a single revolvable shaft mounted in the lugs, gears on the ends of the shaft adapted to coact 70 with the gears on the pivot pins, an arm pivotally mounted on the upper end of each semi-circular bracket, cylindrical lugs on the end of each arm provided with stops, a shaft fixed in the lugs, arms pivoted on the shaft 75 and held in position by the stops, and a copy holding carriage pivotally mounted on the arms.

8. A device of the kind described comprising two adjustable clamps, a semi-circular bracket mounted in each clamp on a pivot pin, a gear on the end of each pivot pin, lugs depending from the clamps, a single revolvable shaft mounted in the lugs, gears on the ends of the shaft adapted to coact 80 with the gears on the pivot pins, an arm pivotally mounted on the upper end of each semi-circular bracket, cylindrical lugs on the end of each arm provided with stops, a shaft fixed in the lugs, arms pivoted on the shaft 90 and held in position by the stops, a plate pivotally mounted on the arms, said plate being provided with two pairs of upstanding lugs, a shaft revolvably supported by each pair of lugs, and a movable copy holder 95 supported by said shafts.

In testimony whereof I have hereunto subscribed my name in the presence of two subscribing witnesses:

CLARENCE H. CALDWELL.
